UNITED STATES PATENT OFFICE.

WILLARD ORD LATHROP, OF CINCINNATI, OHIO.

BEDSPRING STRUCTURE.

Application filed August 8, 1927. Serial No. 211,445.

This invention relates to bed-spring structures in which upright conical or helical wire springs are used between supporting-frames and each of such springs is closely-wound 5 and in contracted horizontal diameter at its middle portion (mid-height, so to speak) so that a telescoping or socketing cross-intersection of tie-devices can be employed within said respective closely-wound and contracted 10 middle portions and thereby simply, economically and effectively preserve or maintain the constant perpendicular alignment of said springs and amply prevent their sagging or lateral displacement, shifting, or distortion, 15 while not otherwise materially affecting their desired and intended resiliency for continued or extended comfortable compression-use.

The specific and preferred form of interlocking and stabilizing device herein will be 20 fully described in connection with the accompanying sheet of drawings, in which—

Figure 1 is a plan view of a miniature assembly of bed or seat springs, showing the usual border-frames for their properly- 25 related support and with the intersecting lock-tie devices embodying my improvement herein in working position; Fig. 2, an end elevation of Fig. 1, bringing more clearly to view my improved tie-feature; Fig. 3, a side elevation of Fig. 1, but at right-angles to Fig. 2; Fig. 4, a fragmentary elevation of the central closely-wound and contracted portion of an adjoining pair of spiral springs to which my invention is especially adapted, 30 and showing one end of the unbent or straight cross-tie wire used by me and how it is assembled with the arched or humped and U-crimped form of longitudinal wire also used by me in the special form of intersections 35 40 with said unbent or straight cross-tie wires for upholding and stabilizing the perpendicular springs midheight; Fig. 5, a view similar to Fig. 4, but taken at right-angles thereto; Fig. 6, a fragmentary elevation of one end 45 of the said arched or humped and U-crimped form of longitudinal wire, and showing, in section, the relation of the said unbent or straight cross-tie wire and the said closely-wound and contracted center coils of the said 50 adjoining pair of springs that are also in section in seated-place in the U-crimped portions of the wire at the opposite ends of the respective arches or humps in the said longitudinal wire; Fig. 7, a fragmentary sectional elevation of one attaching-end of the 55 said unbent or straight cross-tie wire and

showing, in section, its engaging intersecting-relation with the said arched-portion of the longitudinal wire but omitting the springs; Fig. 8, an elevation of one of the longitudinal 60 special form of arched and U-crimped wires used in my improved binding-intersections for bed-springs; Fig. 9, a longitudinal elevation of the straight cross-tie wire used in my special form of binding-intersections; 65 and Fig. 10, a full-size fragmentary sectional elevation, taken on the dotted-line 10, 10, of Fig. 4, of the improved assembled cross-tie or composite intersection herein, showing the said closely-wound and contracted central 70 portion of the spring in section, the arched and U-crimped unit of one of the longitudinal tie-wires in engagement with said closely wound and contracted central portion of the 75 spring and a cross-section of one of the said unbent or straight cross-tie wires in interlocking engagement with the said arched-portion of its coacting longitudinal binding-wire.

A indicates each one of the perpendicular spiral springs used in a bed or other similar-cushioned structure that I have shown, for immediate example and convenience, on a small scale in Figs. 1, 2 and 3, in assembled form on a pair of angle-irons *a*, *a*, that are 80 connected by means of a longitudinal series of transverse bars or rods *B* on which the rows of spirals are mounted, the latter as best seen in Fig. 2.

The springs shown are conical from their 90 broad upper ends or top coils down to their closely-wound cylindrical middle portions or centers *C* and thence are cylindrical or of the same uniform horizontal diameter as portions *C* down to their lower ends or bases *b* 95 that are ordinarily hooked to the said transverse bars *B*. The said middle portions *C* of the springs comprise a plurality of closely-wound and contracted strength-enhancing coils so as to further provide an inclosure or 100 a chamber for the reception of my improved form of very simple, economical and effective interlocking-intersections of tie and binding wires that I will now proceed to briefly and specifically describe.

In Fig. 8, I best show the peculiar or preferred form of longitudinal wires 11, and, in Fig. 9, I best show the peculiar or preferred form of cross or transverse tie-wires 12 used in said several interlocking-intersections of the spring-structure herein. The said longitudinal wires 11 have a series of straight or 110

unbent portions 13 that are alternated by upwardly-arched or hump portions 14, the latter being flanked by depressed crimps or socket-members 15, 15, of U-shape. The said straight portions 13 lie between the central contracted coils C, and the said crimps 15, 15 form sockets or seats for the latter, with the said arched or hump portions 14 extending upwardly and snugly encased within the said central contracted coils C, as best seen in Figs. 5 and 10. The said arch-members 14 have their high-point 14^a extending approximately the thickness of the spring wire above the level of the top coil of said contracted middle section C of the respective springs for the reception of the straight cross-tie wires 12 that lie transversely in the bed-structure and readily pass through the lower coils of the conical upper sections of the springs for due hooking-
engagement at their opposite ends 12^a, 12^a, with the said lower coils of the conical upper sections of the border springs that lie along the opposite sides of the bed, the latter feature being as best seen in Figs. 1 and 2. In assembling the intersecting wires, the longitudinal arched and crimped wires 11 are each inserted from the side of the row or series of contracted spring-centers C, after lining the arched-portions up with each of the latter the length of the bed and then inserting the arches or humps into place in each chamber or casing formed by said central contracted coils C with the latter resting in the respective side-crimps 15 and then the transverse straight wires 12, with unbent ends, are easily inserted through the open lower coils of the conical upper sections of the row of springs until they pass entirely across all the springs in that row, so that their opposite ends 12^a can then be bent upwardly into hook-form, as best seen in Figs. 2, 4 and 7, and thus completing the interlocking of the spirals at their central closely-wound and strong contracted portions, proof against any lateral or torsional displacement or any sagging of the spirals from their true perpendicular standing-support on the lower cross-bars B. It will be well observed, in Fig. 7, how very simple the intersections of tie-wires hereinafter are for effecting the ready united interlocking or coupling of the cluster of perpendicular cushioning-springs in a bed-structure that cannot sag or sway sidewise, but must always rise and fall in a perfectly perpendicular path on the compression of the

spring-units by a weight of any kind on the bed. The spring-structure, as a whole, can be very easily taken apart at any point therein, in the event one or more of the spring-units needs replacing or repair, by simply opening one of the hooked ends 12^a of that one of the straight cross-tie wires 12 in which the repairs are to be made and then drawing that wire lengthwise until the faulty spring or wire is reached for substitution by a good one or other repairs thereto. After such substitution or repairs the said withdrawn straight wire 12 is pushed or drawn back into its original coupling-position for again hooking its said opened end 12^a into fastened-place on the contracted middle-portion C of its proper border-spring next adjacent the side-bar of the bed-frame.

Ordinary X-crossed intersecting auxiliary coils 16 are used between the rows of spirals A for hook-connection with the topmost coils of the latter and duly aligning the upper level of the bed-spring structure in unit-form, as customary.

I claim:—

A bed-spring structure comprising, in combination, a plurality of perpendicular spirals each of which has a contracted closely-wound intermediate section of a plurality of four or more coils, supports for said spirals in transverse rows along the structure, a border-frame surmounting the structure, longitudinal wires having straight portions therein that alternate arched or humped portions with deep straight sides, the said deep straight sides of the humped portions forming with companion deep straight sides deeply depressed U-shape seating wells or sockets for the reception of said closely-wound four-or-more coiled intermediate sections, and straight or unbent cross-tie wires transversely arranged along the rows of spirals and adapted for engagement with the top surface of each of the uppermost coils of the intermediate sections and beneath the high-point of the respective hump portions of the said longitudinal wires for interlocking-engagement in an unshiftable manner therewith and likewise with the said contracted intermediate sections, substantially as shown and described.

In testimony whereof I hereunto affix my signature.

WILLARD ORD LATHROP.
